[57] CLAIM

The ornamental design for a sheetrock hanger construction shoe, as shown and described.

DESCRIPTION

FIG. 1 is a bottom perspective view of a sheetrock hanger construction shoe showing my new design;
FIG. 2 is a front end elevational view thereof;
FIG. 3 is a rear end elevational view thereof;
FIG. 4 is a side elevational view thereof, the side opposite being a mirror image of the side shown in FIG. 4;
FIG. 5 is a top plan view thereof; and,
FIG. 6 is a bottom view thereof.

FIG.1.

FIG. 3.

FIG. 2.

FIG. 4.

FIG. 6.

FIG. 5.
